UNITED STATES PATENT OFFICE

NATHAN F. HOPKINS, OF ROCKLAND, MASSACHUSETTS, ASSIGNOR TO UNITED SHOE MACHINERY CORPORATION, OF PATERSON, NEW JERSEY, A CORPORATION OF NEW JERSEY

LOCKSTITCH SHOE SEWING MACHINE

Application filed February 9, 1929. Serial No. 338,751.

The present invention relates to lockstitch shoe sewing machines of the so-called McKay type which comprise a straight hook needle, a shuttle, a shoe supporting horn arranged to extend inside of the shoe and a needle threading whirl located in the horn.

The invention is herein illustrated as embodied in a lockstitch shoe sewing machine of the McKay type which is intended as an improvement on the machine disclosed in the pending application of Bernard T. Leveque for a lockstitch sewing machine, filed February 18, 1927, Serial No. 169,203, although certain features of the invention are not limited to use in a machine having its various parts constructed and arranged as in the machine of the Leveque application but may be embodied in other types of lockstitch McKay sewing machines.

In the machine disclosed in the Leveque application and also in certain other McKay lockstitch sewing machines a take-up is provided for pulling the needle thread from the shuttle down towards the work, a portion of the loop, however, being left standing above the work so that the needle, during its retracting stroke, can draw thread from the loop. Also, in these machines, the shuttle is utilized to draw thread from the supply as the loop of needle thread passes over the shuttle. The construction, arrangement and timing of the parts of these machines necessitates that the needle loop be drawn from the shuttle by the take-up while the thread is being wound around the needle by the whirl, and also that the thread be pulled from the supply by the shuttle while the whirl is in such a position as to cause the thread to be bent sharply over the edge of the opening in the plate covering the whirl and forming the top surface of the horn. Consequently the thread is subjected to considerable strain and friction during both of these operations with a consequent liability of injury to the thread and interference with the proper formation of the stitches of the seam.

The object of the present invention is to remedy the defects above noted in the operation of lockstitch McKay shoe sewing machines and produce a construction and ar-

rangement of parts which will not only facilitate the operations of drawing thread from the supply as the needle loop passes over the shuttle and of taking up the needle loop, but will also enable the needle to be threaded more readily and with greater certainty.

With the above object in view, the present invention contemplates arranging the needle in the machine so that the needle barb or open side of the needle faces at an angle to the line of feed on the shuttle side of the needle and contemplates threading the needle by rotating the whirl in a direction which will carry the thread first to the shuttle side of the needle. In lockstitch McKay shoe sewing machines, as ordinarily constructed, this causes the whirl, when viewed from above, to rotate in a clockwise direction. By arranging the needle with its barb facing at an angle to the line of feed and by rotating the whirl in a clockwise direction the thread is laid in the hook of the needle before the whirl has made a half revolution, and the take-up can act before the thread has been wrapped around the needle to such an extent as to interfere with the proper taking up of the loop, or to put any injurious friction thereon. Also, at the time the needle loop is passing over the shuttle and thread is being pulled from the supply, the hole in the whirl can be substantially at its greatest distance from the last needle hole so that the thread leads substantially in a straight line to the needle hole and is not bent sharply over the edge of the plate covering the whirl. With the parts constructed and arranged to operate in accordance with the present invention, there results a decided improvement in the ease and certainty of handling a thread by the needle, take-up and shuttle, with less injury to or breakage of the thread, and with a lessening of the strain and wear on the operating parts of the machine.

Referring to the drawings accompanying this application, Fig. 1 is a view in side elevation of a lockstitch shoe sewing machine of the McKay type embodying the invention; Fig. 2 is a detail view illustrating somewhat diagrammatically the position of the whirl with relation to the needle at substantially

the conclusion of the taking-up action of the take-up; and Fig. 3 is a detail view illustrating somewhat diagrammatically the position of the whirl with relation to the last needle hole while the thread is being pulled from the supply as the needle loop passes over the shuttle.

Except as hereinafter described, the machine illustrated in the drawings is the same in the construction, arrangement and mode of operation of its various parts as the machine disclosed in the application of Bernard T. Leveque hereinbefore referred to. The machine comprises a column 2, in the lower portion of which is mounted an electric motor 4 by which the cooperating parts of the machine are driven. The main cam shaft is indicated at 6 and is journaled in the upper portion of the column. The shaft 6 is driven from the motor 4 through a clutch 8, horizontal shafts 10 and 12 in the base of the machine, and a vertical shaft 14. The clutch 8 is controlled from a treadle lever 16 by means of which the clutch may be actuated to connect and disconnect the shafts 10 and 12 from the source of power.

The shoe supporting horn is indicated at 18 and is provided in its tip with a whirl 20 of usual construction which is driven through suitable connections from the vertical shaft 14, these connections being the same as those disclosed in the Leveque application except for the provision of an intermediate bevel gear 22 in the connections between the horizontal shaft 24 and the vertical shaft 26 at the axis of rotation of the horn. The provision of this intermediate gear causes the whirl to rotate in a clockwise direction when viewed from above which is the direction opposite to the direction of rotation of the whirl in the machine of the Leveque application.

The needle of the machine is indicated at 28 and this needle as well as the shuttle, indicated diagrammatically at 30 in Fig. 2, and the take-up of the machine are actuated by the same mechanisms as the corresponding parts of the machine disclosed in the Leveque application.

As clearly shown in Fig. 2, the needle 28 is arranged in the machine with its barb or open side facing at an angle to the line of feed on the shuttle side of the needle and the whirl 20 rotates in a direction to carry the thread first to the shuttle side of the needle or, in other words, to that side of the needle towards which the barb or open side faces. In the machine of the Leveque application, the shuttle is actuated through connections from the needle actuating lever so that the shuttle passes through the needle loop during the downward movement of the needle, the relative positions of the shuttle and needle at the limit of the downward stroke of the needle being substantially as indicated in Fig. 2. In order to thread the needle properly, the whirl 20 must

be so arranged that the thread will be passed around the needle after it enters the whirl, and by having the whirl pass the thread first to the shuttle side of the needle, the threading of the needle by the whirl can be timed with relation to the taking-up action of the take-up so that the take-up action is substantially completed as indicated in Fig. 2 before the thread has been completely wound around the needle or wound around so far as to interfere with the taking-up action.

Upon inspection of Figs. 2 and 3 it will be noted that at the time the take-up is acting and also at the time the needle loop is being passed over the shuttle and thread is being drawn from the supply, the work has been fed, so that the last needle hole has been brought slightly beyond the edge of the hole in the cover plate 32 which holds the whirl in place in the horn. After the work is fed therefore, the thread leads from the thread hole in the whirl to the needle hole across the edge of the opening in the cover plate. From an inspection of Fig. 2, it will be seen that during the action of the take-up the thread leads from the last needle hole to the needle in a nearly horizontal plane so that there is no sharp bend produced in the thread at the edge of the hole in the cover plate tending to put a frictional resistance on the thread and possibly injure the thread. From an inspection of Fig. 3, it will be seen that during the action of the shuttle in pulling thread from the supply, the thread will also lead in a substantially horizontal plane from the last needle hole to the thread hole in the whirl so that at this time in the operation also there will be no sharp bend formed in the thread at the edge of the cover plate. Consequently, both during the taking-up action of the take-up and the pulling-off action of the shuttle, the thread leads through the whirl to the last needle hole in such a manner as to form the least possible resistance to the manipulation of the thread.

The nature and object of the present invention having been indicated and a machine embodying the invention having been specifically described, what is claimed is:

1. A lockstitch shoe sewing machine of the McKay type having, in combination, stitch forming devices including a shuttle, a straight hook needle arranged with its barb facing at an angle to the line of feed on the shuttle side of the needle, a take-up acting to draw the needle loop after passing over the shuttle down towards the work while the needle is in the work, a horn arranged to extend within the shoe, a needle threading whirl located in the horn, and means for rotating the whirl in a direction to carry the thread first to the shuttle side of the needle and to complete the winding of the thread around the needle after the taking-up action has ceased.

2. A lockstitch shoe sewing machine of the

McKay type having, in combination, stitch forming devices including a straight hook needle arranged with its barb facing at an angle to the line of feed, a shuttle on the side 5 of the line of feed towards which the needle barb faces acting to pull off thread from the supply as the needle thread passes over the shuttle, a horn arranged to extend within the shoe, a needle threading whirl located 10 in the horn and means for rotating the whirl in a direction to carry the thread first to the shuttle side of the needle timed with relation to the shuttle to cause the thread to lead in a substantially horizontal plane from the last 15 needle hole to the thread hole in the whirl during the thread-pulling action of the shuttle.

3. A lockstitch shoe sewing machine of the McKay type having, in combination, stitch 20 forming devices including a straight hook needle arranged with its barb facing at an angle to the line of feed and acting on its retracts stroke to draw thread from the preceding needle loop, a shuttle on the side of 25 the line of feed towards which the needle barb faces, acting to pull off thread from the supply as the needle thread passes over the shuttle, a take-up acting to draw the needle loop after passing over the shuttle down towards 30 the work while the needle is in the work, a horn arranged to extend within the shoe, a needle threading whirl located in the horn, and means for rotating the whirl in a direction to carry the thread first to the shuttle 35 side of the needle timed to cause the thread to lead in a substantially horizontal plane from the last needle hole to the thread hole in the whirl during the thread-pulling actions of the take-up and shuttle.

40 4. A lockstitch shoe sewing machine of the McKay type having, in combination, stitch forming devices including a shuttle, a straight hook needle arranged with its barb facing at an angle to the line of feed on the 45 shuttle side of the needle, a take-up acting to draw the needle loop after passing over the shuttle down towards the work while the needle is in the work, a horn arranged to extend within the shoe, a needle threading whirl 50 located in the horn, and means for rotating the whirl in a direction to carry the thread first to the shuttle side of the needle, timed to complete the winding of the thread around the needle without interfering with the tak- 55 ing-up action.

In testimony whereof I have signed my name to this specification.

NATHAN F. HOPKINS.
